(57) **CLAIM**

The ornamental design for a tube, as shown and described.

DESCRIPTION

FIG. 1 is a top perspective view of a tube in accordance with my new design;

FIG. 2 is a front elevational view thereof;

FIG. 3 is a side elevational view thereof; and,

FIG. 4 is a bottom plan view thereof.

The broken lines in the figures are for the purpose of showing unclaimed environmental structure only and form no part of the claimed design.
